UNITED STATES PATENT OFFICE.

TRACY J. BARRY AND HERMAN O. SIDENFADEN, OF ST. JOSEPH, MISSOURI.

CUFF DEVICE.

Application filed January 11, 1926. Serial No. 80,605.

This invention relates to a cuff device for use in connection with the insane, delirious, etc., and has for its object to provide a device of such class, in a manner as hereinafter set forth, for connection to the wrist or ankle and further connected with the body of a patient, or to a permanent structure for use as a precaution to repulse and restrain patients who are insane, delirious, etc.

Further objects of the invention are to provide a cuff device, in a manner as hereinafter referred to and for the purpose set forth, which is simple in its construction and arrangement, strong, durable, adjustable, conveniently connected to the patient, thoroughly efficient in its use, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is an elevation of a cuff device, in accordance with this invention, and further illustrating the adaptation thereof in connection with the wrist of a patient and further anchored to a permanent structure, the arm of the patient and the permanent structure being illustrated in dotted lines.

Figure 2 is a fragmentary view, in front elevation, with the cuff device extended.

Figure 3 is an edge view thereof, partly in section.

Figure 4 is a section on line 4—4, Figure 2.

Referring to the drawings in detail, a cuff device in accordance with this invention, comprises a cuff member 1 formed of flexible material and of a length whereby the same can be bent in circular form to surround wrists or ankles of different sizes. The cuff member 1 is rectangular in contour and consists of a body portion 2 of any suitable flexible material, preferably leather and which has secured to its inner face a flexible lining 3 of any suitable soft material, preferably chamois skin. The lining 3 is of greater length and width than the body portion 2 and is bent to oppose each edge of the

body portion 2 and further to overlap the marginal portion of the outer face of the body portion 2 throughout. That part of the lining 3 which abuts against the edges 60 of the body portion 2 is indicated at 4, and that part which overlaps the marginal portion of the outer face of the body portion 2 is indicated at 5. The part 5 is secured throughout to the body portion 2 65 by a row of stitching 6 and the said row secures the lining 3 tightly against the inner face of the body portion 2.

Connected to the outer face of the body portion 2 and of less width and greater 70 length than the cuff member 1 is a fastener element, referred to generally by the reference character 7, and which consists of a strap 8 of substantial length, provided at one end with a buckle 9, a loop 10 in proximity to the buckle 9, and said strap 8 is furthermore provided with a lengthwise extending row of openings 11, whereby the fastener element 7 can be adjustably secured together to provide for fastening the cuff 80 member 1 to wrists or ankles of various sizes. The inner terminal portion of the strap 8 is secured by rows of stitching 12 to the outer face of the body portion 2, at a point between the transverse median and one end 85 of the latter. The row of stitching 12 does not extend through the lining 3. The inner end of the strap 8 is spaced from the adjacent end of the cuff member 1 and further the buckle 9 projects slightly beyond such 90 end. The free end of the strap 8 extends a substantial distance from the other end of the cuff member 1.

Secured to the body portion 2 of the cuff member 1, at the transverse median thereof 95 by a row of stitching 13, is a coupling member 14 which extends from the cuff member 1 at right angles thereto. The coupling member 14 is in the form of a strap and it is of a length for anchoring the cuff member 1 around the body of the patient or to a stationary structure or other object, such as the head of a bed. The coupling member 14 has its inner end positioned at one side of the strap 8, or in other words the 100 strap 8 does not extend over the inner end of the coupling member 14.

By way of example the cuff device in Figure 1 is illustrated as secured to the wrist of a patient and anchored to the head of 110 a bed. In Figure 1 the arm of the wearer is shown in dotted lines and indicated at 15,

and the head of the bed is indicated at 16 and indicated in dotted lines.

A cuff device, in accordance with this invention, when employed, acts as a precaution to repulse and restrain patients who are insane, delirious, etc., and can be connected to the wrists or ankles or body of the patient, or instead of the body of the patient, anchored to a suitable structure, and it is thought the many advantages of a cuff device, in accordance with this invention, can be readily understood, and although the preferred embodiment of the invention is as illustrated and described, yet it is to be understood that changes in the details of construction can be had which will fall within the scope of the invention as claimed.

What we claim is:—

1. A cuff device for the purpose set forth comprising a foldable and flexible cuff member of rectangular contour, an adjustable fastener element extending lengthwise of and of less width than the width of the cuff member, said fastener element having a por-

tion of its length secured to the outer face of the cuff member, and a coupling member secured to the outer face of the cuff member and extending at right angles to the forward edge of the latter, said cuff member including a lining of soft material, and that part of the secured portion of the fastener element being of less length than the remaining portion of said element.

2. A cuff device comprising a foldable and flexible cuff member of rectangular contour, a fastener element secured to the outer face of the cuff member and providing means for adjustably securing the cuff member to the wrist or ankle of a patient, and a coupling member secured to the cuff member, extending at right angles to the forward edge of the latter and providing means for anchoring the cuff member when secured to the wrist or ankle of a patient.

In testimony whereof, we affix our signatures hereto.

HERMAN O. SIDENFADEN.
TRACY J. BARRY.
